INVENTOR

Albert Smith.

BY Fisher & Moore ATTYS.

UNITED STATES PATENT OFFICE.

ALBERT SMITH, OF CLEVELAND, OHIO.

FOLDABLE PLUMBER'S STAND FOR VISES.

987,180.

Specification of Letters Patent. Patented Mar. 21, 1911.

Application filed December 22, 1909. Serial No. 534,431.

To all whom it may concern:

Be it known that I, ALBERT SMITH, a citizen of the United States, residing at Cleveland, in the county of Cuyahoga and State 5 of Ohio, have invented certain new and useful Improvements in Foldable Plumbers' Stands for Vises, of which the following is a specification.

My invention relates to a foldable plumber's stand for vises, all as hereinafter fully described and particularly pointed out in the claims.

In the accompanying drawing, Figure 1 is a perspective view of the stand unfolded 10 and temporarily erected for use, and Fig. 2 is a perspective view partly in section of a union joint in the central brace.

The invention is designed to be used by plumbers for supporting vises in unfinished 15 or skeleton buildings.

It frequently occurs that plumbers have to do much of their work in buildings before any floors have been laid and wherein it is difficult to place or affix a vise in such a 20 way that work can be advantageously done thereon, and hence I conceived the present invention which consists in a special vise support which affords a firm and convenient rest upon which the vise can be rigidly affixed and is held as securely for all practical 25 purposes as on an ordinary work bench or other fixed support.

To these ends I have devised a two section skeleton frame comprising a top or working 30 section or portion *a*, and a front upright section or portion *c*, and said sections are hinged together in the angles or corners thereof at *d* and adapted to fold into a close and compact form one upon the other and 35 to open to a position at right angles to each other as seen in Fig. 1. A single two-part tubular brace *b* preferably made of pipe sections connects the lower edge or base of section *c* with the outer edge of section *a*, and 40 is pivoted at both ends on said frame and provided with a union joint 4 at the middle so as to be separable and folded with the sections. The said frame or stand is preferably constructed of angle iron or steel, and 45 both sections are narrowed at their meeting ends as indicated by the inward curvatures 2 and 3 respectively to afford convenient approach by the workman to the vise. The 50

said sections are at right angles to each other when open and the bottom of section 55 *c* is wide enough to extend across at least two joists *J* while the outer end of section *a* is wide enough to extend across two studdings *S* and is adapted to rest on pins 7 while the upright section is confined by 60 pins 7 in said joists.

The upper horizontal section *a* is provided with two converging side pieces or wings 5 integral with or fixed rigidly upon the bars or sides of said section in any strong and 65 sufficient way and in the narrowed portion thereof relatively near to section *c*. Said side pieces or wings incline inward toward each other bottom to top as well as converge toward each other at one end so that thereby the vise can be tightened therein and also be easily removed. A bolt hole 6 between 70 said wings serves to further secure the vise in place.

When folded the two sub-frames or sections *a* and *c* match each other at all their 75 edges but when erected as shown are braced by brace *b* and otherwise secured by the several pins 7 top and bottom.

What I claim is:

1. A plumber's stand consisting of two skeleton sections having straight and relatively wide outer rest edges and narrowed inner edges hinged together, a jointed brace connecting said outer edges and transverse 85 cross pieces in said narrowed portions of the frame converging to one side thereof and inwardly inclined.

2. A plumber's vise stand adapted to support vises in unfinished buildings and consisting of open work horizontal and vertical frames respectively hinged together and adapted to be folded and unfolded and an angularly disposed brace connecting the otherwise free edges of the said frames, the 95 said frames being narrowed at their hinged edges as compared with their opposite edges and the said horizontal frame provided with means in its narrowed portion to affix a vise.

In testimony whereof I affix my signature 100 in presence of two witnesses.

ALBERT SMITH.
